UNITED STATES PATENT OFFICE.

ROWE HARTSON, OF PROCTOR, TEXAS.

CLOCK DIAL.

Application filed April 23, 1924. Serial No. 708,500.

To all whom it may concern:

Be it known that I, ROWE HARTSON, a citizen of the United States, residing at Proctor, in the county of Comanche and State of Texas, have invented new and useful Improvements in Clock Dials, of which the following is a specification.

An object of this invention is the provision of a clock dial for a clock employed in school rooms, with means for indicating thereon the study periods for different subjects to be learned by the scholars.

To the attainment of the foregoing, the invention consists in the improvement as hereinafter described and definitely claimed.

In the drawing:—

Figure 1 is a front elevation of the improvement.

Figure 2 is a detail sectional view on the line 2—2 of Figure 1.

The clock illustrated in Figure 1 of the drawing is provided with a single hand 1, but the dial plate 2 thereof has inscribed thereon not only numerals indicating the hours but the fraction of hours. The fractional numerals are arranged in radially disposed blocks 3. This construction of clocks is old and well known and I make no claim thereto. However, in carrying out my invention I make use of a larger size dial than is ordinarily employed, and at the outer terminal of the blocks or divisions 3 I form the dial plate 2 with a continuous depression 4. This annular depressed portion is designed to have received therein segmental strips of paper which have impressed on their outer faces radial blocks designed to be arranged in alignment with the blocks or divisions 3 on the dial. These segmental paper strips are broadly indicated by the numeral 5, and the division lines 6 thereon may be in the nature of fold or kerfed lines, whereby the teacher may remove certain of the blocks from each of the segments to ac-

cord with the length of the time for the 45 study period of the subject which is imprinted on the said segments. Usually the study period is for three-fourths of an hour and the segmental paper blocks 5 are of a length corresponding with the number of divisions or blocks 3 on the dial indicating this period of time. The several segmental blocks 5 have imprinted on their outer faces the different studies to be taken up during the entire school period, including the recess 50 periods and the noon hour. Preferably the segmental blocks having the titles of different studies imprinted thereon are differently colored, and are likewise numbered to indicate the study periods.

The segmental paper blocks 4 are centrally folded upon themselves and have their confronting faces formed with a curved recess. In this recess there is received a flat spring metal ring 7. The ring is in the nature of a split member, but has its ends connected by means 8 (Figure 1). The ring exerts a sufficient tension against the walls provided by the recesses in the segmental blocks to hold the same in engagement with the flanges 60 provided by the continuous recesses 4 in the dial 2.

Having described the invention, I claim:—

A dial for a clock designed for use in schools in which the said clock is provided with a single hand, and the dial thereof is provided with figures indicating the hours and having radial blocks between the hour figures in which the minute figures are imprinted, said dial outward of said blocks 75 having a continuous depression, segmental blocks having imprinted thereon study subjects received in the depression, and a split ring member passing centrally through the segmental blocks.

In testimony whereof I affix my signature.

ROWE HARTSON.
